Primary Examiner — Elizabeth A Albert*Assistant Examiner* — Karen E Eldridge Powers*(74) Attorney, Agent, or Firm* — McHale & Slavin, P.A.(57) **CLAIM**

The ornamental design for a hose reel enclosure, as shown and described.

DESCRIPTION

FIG. 1 is a perspective view of the hose reel enclosure of the instant invention;

FIG. 2 is a front view thereof;

FIG. 3 is a rear view thereof;

FIG. 4 is a right side view thereof;

FIG. 5 is a left side view thereof; and,

FIG. 6 is a top view thereof.

The broken lines immediately adjacent the shaded areas represent the bounds of the claimed design, while all other broken lines represent features of the article to which the claimed design is applied. None of the subject matter shown in broken lines forms a part of the claimed design.
